(57) **CLAIM**

The ornamental design for a three dimensional wind ornament with a central spherical element, as shown and described.

DESCRIPTION

FIG. 1 is a top, front and right side perspective view of the circular embodiment of our new design for a three dimensional wind ornament with a central spherical element;

FIG. 2 is a top plan view thereof;

FIG. 3 is a front elevational view thereof;

FIG. 4 is another front elevational view shown on an enlarged scale;

FIG. 5 is a top, front and right side elevational view of the square embodiment of our new design;

FIG. 6 is a top plan view thereof;

FIG. 7 is a front elevational view thereof; and,

FIG. 8 is another front elevational view thereof shown on an enlarged scale.
